Primary Examiner — Kevin K Rudzinski*Assistant Examiner* — Paul D Bohannon(74) *Attorney, Agent, or Firm* — Brian Harrod; George W. Moxon, II(57) **CLAIM**

The ornamental design for a seat for a bed, as shown and described.

DESCRIPTION

FIG. 1 is a perspective view showing my new design of a seat for a bed in the deployed position;

FIG. 2 is a front view thereof;

FIG. 3 is a left side view thereof, the right side view is a mirror image of the left side;

FIG. 4 is a top view thereof;

FIG. 5 is a rear view thereof;

FIG. 6 is a bottom view thereof;

FIG. 7 is a perspective view showing my new design in the folded/storage position;

FIG. 8 is a front view thereof;

FIG. 9 is a left side view thereof;

FIG. 10 is a top view thereof; and,

FIG. 11 is a right side view thereof.

The broken lines shown in the drawings are for the purpose of illustrating portions of the article and form no part of the claimed design.

1 Claim, 4 Drawing Sheets(56)
